COLLAPSIBLE DISPENSING TUBE

Ray J. Heskes, St. Louis, Mo.

Application June 15, 1956, Serial No. 41,900

Term of patent 3½ years

(Cl. D58—17)

FIG. 1.

FIG. 2.

Fig. 1 is a top plan view of a collapsible dispensing tube, showing my new design; and Fig. 2 is a side elevation of the same.

The body portion of the tube is conventionally round and the top of the cap portion is flat and plain.

The side not shown is the same as the side shown.

The characteristic features of my design for the collapsible dispensing tube disclosed reside in the configurations of the crimped sealed end portions thereof as shown.

I claim:

The ornamental design for a collapsible dispensing tube, as shown and described.
